[57] CLAIM

The ornamental design for a dose measuring medicinal applicator, as shown.

DESCRIPTION

FIG. 1 is a front elevational view of a dose measuring medicinal applicator showing our new design.

FIG. 2 is a rear elevational view of the dose measuring medicinal applicator shown in FIG. 1; and

FIG. 3 is a perspective view of the dose measuring medicinal applicator shown in FIGS. 1 and 2 with the adhesive cover removed for convenience of illustration.
